OSCAR HEYMAN, OF NEW YORK, N. Y.

BROOCH

Application filed August 8, 1930. Serial No. 473,306.

This invention relates to brooches, and in particular to improvements in convertible brooches.

The common type of brooch comprises a body member, usually jeweled or otherwise decorated, provided on its reverse or under side with a pin by means of which the brooch is secured to the clothing of the wearer. Brooches of this type have been made and 10 worn from time immemorial.

There is another type of brooch which has of late attained considerable vogue and which is generally referred to as a clip brooch. This brooch comprises a decorated body member, but instead of the pin of the common brooch, is provided on its reverse side with a spring-pressed clamping member or jaw which cooperates with the body member to grip a section of the wearer's clothing. Such 20 a brooch may be snapped over the hem of a gown at the throat or shoulder for purely decorative purposes, used for gathering the bertha of a dress, to secure a scarf, or employed in divers ways which need not here be 25 enumerated.

Attempts have been made to make a convertible brooch, one in which two clip brooches may be assembled and used as a single pin brooch and then disassembled and 30 used separately. (By this means ownership of three brooches can be acquired for the price of two—a consideration of some importance when expensive jewelry is involved.) Thus two clip brooches are placed 35 together, end to end and held so by means of a plate, or other connecting member extending across their under sides and screwed in place.

This plate being provided with a pin converts the two clip brooches, their clamping 40 members temporarily inoperative, into a common ordinary pin brooch—that is to say, after a fashion.

Doubtless after the connecting plate is 45 screwed onto the clip brooches a single brooch results, but the modus operandi is not satisfactory. The little screws get lost. The operation is laborious and does not commend itself to those who wear brooches. Then too such a combination brooch is likely to be 50 clumsy.

In accordance with the present invention I have provided a pair of clip brooches and means for quickly and easily joining them to form a single pin brooch. The operation, both of assembling and disassembling can be 55 performed in a twinkling by any one. No screws are required and the combination brooch is neat, strong and handsome. At the same time I have eliminated the separate springs commonly used in connection with 60 the clamping members of the clip brooch units and have greatly improved the appearance and efficiency thereof.

The improved clip brooch of my invention comprises a body on which is pivotally 65 mounted a resilient clamp, preferably U-shaped. The ends of this clamp are provided with opposed journal pins supported within spaced bearings on the body. The bearings and clamp ends are provided with coacting 70 cam faces so designed that as the clamp is swung outward its arms are spread and the clamp thus placed under tension which urges its return into contact with the body until it reaches a neutral position at approximately 75 45° to the body. Beyond this the clamp is biased toward a vertical position. The cam faces are so designed that in both limiting positions, the horizontal and vertical, the parts snap into fixed position and the tension 80 on the clamp is relieved. The cooperating faces of the clamp and body are, of course, provided with means for gripping the clothing of the wearer. This clip brooch has no separate spring and relies for its effectiveness 85 on the natural resiliency of the clamping member.

In order to assemble two of these clip brooches to form a pin brooch I provide a bar which extends across the backs of the 90 clip brooches when they are laid end to end and passes between the spaced bearings on each brooch. This bar is provided with holes which are alined with the journal pins. When the clamps are swung downward into 95 contact with the body these journal pins, due to the design of the cam faces and the resilience of the clamps, are moved axially and pass into the holes on the bar; thus the two clip brooches are held firmly altogether 100

and form a single brooch which may be used in the ordinary manner. The bar is, of course, provided with the usual safety pin.

In the accompanying drawing I have illustrated a preferred embodiment of my invention. In the drawing, Figure 1 is a perspective view of the assembled brooch; Figure 2 is a plan view of the brooch when assembled; Figure 3 is an enlarged transverse section 10 taken along line 3-3 of Figure 2, illustrating the manner in which the journal pins are mounted and the manner in which they enter the holes in the common connecting bar; Figure 4 is a detail showing the structure of the 15 coaxing cam faces, the journal pins being illustrated in retracted position; Figure 5 is a detail of the connecting bar and Figure 6 is a perspective view showing the relation of the parts during assembly or disassembly 20 and before the connecting bar has been secured in place.

The clip brooch illustrated comprises a body 10 having a jeweled or otherwise decorated face 11. On the back, or reverse side, a 25 resilient U-shaped clamp 12 is pivotally mounted in the following manner: The ends of the clamp are inturned and terminate in opposed coaxial journal pins 13 normally urged toward each other by the resiliency of 30 the metal of which the clamp is made. These pins are journaled within bearings 14 mounted upon the body and spaced apart. The outer face of each bearing is provided with a cam face having four equi-spaced notches 35 15 and the corresponding inner face of each inturned end of the clamp is provided with a coaxing cam face having four equi-spaced projections 16 designed to interfit with the notches 15 when the clamp is in either of its 40 limiting positions, horizontal or vertical.

If we assume the parts in closed position as illustrated in Figures 1, 2 and 3 with the clamp lying along the back of the body, the projections 16 lie within notches 15 and 45 the journal pins 13 extend toward each other and almost abut. When the brooch is opened to permit the insertion of a piece of clothing the clamp is swung outward. This swinging movement causes the cam projections 16 to 50 ride up along the sloping side walls of the notches 15, thus spreading the arms of the clamp, retracting the pins 13 and placing the clamp under tension. When the projections 16 have reached the flat outer face of the 55 bearing the parts occupy the position illustrated in Figure 4. Upon swinging the clamping member further upward the projections 16 again enter the notches but in a position removed 90° from the original position. Although the clamp is under tension 60 when the parts are in neutral position, as illustrated in Figure 4, it is moved into horizontal and vertical positions by this tension only when the projections 16 enter the 65 notches 15.

The lower face of the clamp is provided with two downwardly extending points 17, and the body with two upwardly extending series of teeth 18 both of which are designed to bite into the clothing and hold the brooch 70 firmly in position.

The two clip brooches are assembled to form a single pin brooch in the following manner: The clamps 12 are moved into neutral position, as illustrated in Figures 4 and 75 6, in which position the pins 13 are retracted. A connecting bar 19 is thereupon laid across the backs of the two clip brooches, as illustrated in Figure 6. Each end of this bar is provided with a hook 20 which is inserted 80 beneath a loop 21 on the body of each of the brooches and the two snap brooches swung into alignment, the bar passing between the two spaced bearings 14. When the parts are in this position the clamps 12 are swung 85 downward, this movement causing the journal pins 13 to move axially toward each other and enter holes 22 in the bar. The parts are now firmly joined and the two clip brooches converted into a single pin brooch. The bar is, of course, provided with the usual pin 23 90 provided with a safety catch 24. To disassemble the parts, the operations just described are reversed, the clamps swung into neutral to retract the pins 13, and the bar 95 19 removed.

The individual clip brooches of my invention are simple in construction and use, have no separate springs to break, and are strong, durable and attractive. The two can be quickly and simply assembled to form a pin brooch and as quickly and simply disassembled. No mechanical skill is required and no tools. Only one extra part is necessary—a light connecting bar. Thus the inconvenience arising from loss of screws and other parts is minimized and a neat, light and graceful assembly achieved.

I claim:

1. In a clip brooch, the combination of a body, a clamp pivotally mounted thereon and cooperating with the body to clamp the clothing of the wearer, a pin carried by the clamp coaxial with the pivotal axis, a bearing for said pin carried by the body, and coaxing cam faces on the bearing and clamp whereby the pin is given an axial movement as the clamp is swung.

2. In a clip brooch, the combination of a body, a clamp pivotally mounted thereon by means of journal pins carried by the clamp, and cooperating with the body to clasp the clothing of the wearer, bearings for the pins carried by the body, and coaxing cam faces on the bearings and clamp whereby the pins are given an axial movement as the clamp is swung.

3. In a clip brooch, the combination of a body, a U-shaped clamp pivotally mounted thereon by means of opposed journal pins and

cooperating with the body to clasp the clothing of the wearer, spaced bearings for the pins carried by the body and coacting cam faces on the bearings and clamp whereby
 5 the pins are moved axially away from each other as the clamp is swung outward and toward each other as the clamp is swung toward the body.

4. In a clip brooch, the combination of a body, a resilient U-shaped clamp pivotally mounted thereon by means of opposed journal pins and cooperating with the body to clasp the clothing of the wearer, spaced bearings for the pins carried by the body and
 10 coacting cam faces on the bearings and clamp whereby the pins are moved axially away from each other as the clamp is swung outward and toward each other as the clamp is swung toward the body, the cam faces spreading
 15 the arms of the clamp as the latter is swung away from the body thereby putting the clamp under tension and urging its return.
 20

5. A convertible brooch comprising a plurality of juxtaposed units, a removable bar extending across the backs of the units, a pin on each unit, means for passing the pins through holes in the bar to hold it fixed relative to the units, and means on the bar for
 25 securing the combined elements to the clothing of the wearer.

6. A convertible brooch comprising a pair of clip brooches laid end to end, each clip brooch comprising a body, a clamp pivotally mounted thereon and a journal pin carried by the clamp, a removable bar extending across the backs of the brooches, means whereby the journal pins on the clip brooches are passed through holes in the bar to hold it fixed
 35 relative to the clip brooches, and means on the bar for securing the combined elements to the clothing of the wearer.

7. A convertible brooch comprising a plurality of clip brooches laid end to end, a resilient U-shaped clamp pivotally mounted on each clip brooch, opposed journal pins carried by each clamp, spaced bearings for the pins, coacting cam faces on the bearings and clamps whereby the pins are axially retracted
 45 as the clamp is swung outward, and caused to approach each other as the clamp is swung toward the body, a removable bar extending across the back of the brooches and between the spaced bearings, the bar having holes in
 50 alignment with the journal pins through which these pins are passed to hold the bar in fixed relation to the clip brooches, and a safety pin on the bar.

In testimony whereof I affix my signature.

60 OSCAR HEYMAN.
